(57) **CLAIM**

The ornamental design for a shaker lid, as shown and described.

DESCRIPTION

FIG. 1 is a perspective view of a shaker lid showing our new design in a first configuration;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1;

FIG. 7 is a bottom plan view of FIG. 1;

FIG. 8 is a perspective view of a shaker lid in a second configuration;

FIG. 9 is a front elevation view of FIG. 8;

FIG. 10 is a rear elevation view of FIG. 8;

FIG. 11 is a left side elevation view of FIG. 8;

FIG. 12 is a right side elevation view of FIG. 8;

FIG. 13 is a top plan view of FIG. 8;

FIG. 14 is a bottom plan view of FIG. 8;

FIG. 15 is a perspective view of a shaker lid in a third configuration;

FIG. 16 is a front elevation view of FIG. 15;

FIG. 17 is a rear elevation view of FIG. 15;

FIG. 18 is a left side elevation view of FIG. 15;

FIG. 19 is a right side elevation view of FIG. 15;

FIG. 20 is a top plan view of FIG. 15; and,

FIG. 21 is a bottom plan view of FIG. 15.

The broken line shown in each of FIG. 1, FIG. 8 and FIG. 15 is for the purpose of illustrating environment and forms no part of the claimed design. The remainder of the broken lines in the figures depict portions of the shaker lid that form no part of the claimed design.

1 Claim, 15 Drawing Sheets
